UNITED STATES PATENT OFFICE.

WILLIAM G. COUGHLIN, OF PHILADELPHIA, PENNSYLVANIA.

COMPOUND RAILROAD-RAIL.

1,260,148.

Specification of Letters Patent. Patented Mar. 19, 1918.

Application filed March 3, 1916, Serial No. 81,915. Renewed October 13, 1917. Serial No. 196,553.

To all whom it may concern:

Be it known that I, WILLIAM G. COUGHLIN, a citizen of the United States, and resident of Philadelphia, county of Philadelphia, State of Pennsylvania, have invented 5 certain new and useful Improvements in Compound Railroad-Rails, of which the following is a specification.

This invention relates to railroad rails 10 and particularly to compound rails in which the head or wearing portion of the rail is detachable from the continuous supporting member so that it may be removed and renewed without disturbing the supporting 15 member.

It is the object of this invention to provide a rail of this class which is of simple construction, which possesses great strength and stability and which reduces the wearing action 20 of the rail on the tie to a minimum.

The invention will be described in connection with the accompanying drawing, in which,

Figure 1 is a side view of my improved 25 rail mounted upon ties, as in a section of roadbed; and

Fig. 2 is a cross-sectional view of the same enlarged.

Referring to the drawing, A indicates the 30 head member of the compound rail and B the base member. The member A comprises the rail head 10, a tongue 20 extending downwardly and an intermediate neck 21. The base member B comprises a base plate

35 11 and head supporting webs 12, 13, which are integral with the base plate and which extend convergently upward from lines about midway between the center and the edges of the base plate. The upper portions 12 and 13 are thickened and constitute shoulders 14 and 15, respectively, having upper faces 16 and 17 arranged at substantially right angles to the planes of the webs 12 and 13, respectively, and forming 40 bearing surfaces on which corresponding lower surfaces 18 and 19 of the rail head 10 are adapted to rest when the rail head is seated on the supporting base.

The shoulders 14 and 15 are separated 45 only by a narrow slot, and the downwardly

projecting tongue 20 is adapted to be held between the shoulders when the rail head is in place. The thickness of the neck 21 is approximately equal to the width of the slot between the shoulders 14 and 15 while the 55 tongue below the neck is thicker.

The upright webs 12 and 13 are sufficiently resilient to allow the shoulders 14 and 15 to spring apart a sufficient distance to permit the passage of the tongue 20 in 60 seating the rail head on the base member, and to cause the shoulders to spring back into normal position to engage the neck 21 after the thicker portion has passed through. Considerable force is required to seat or unseat 65 the rail head in this manner, which may be applied by any well known method, as by hammers, clamps, etc.

The head 10 might be maintained in position on the support by the locking action of 70 the shoulders 14 and 15 alone but to render the structure secure and to prevent vibration and "creeping" of the head relatively to the support, a series of horizontally disposed bolts 22 are provided which are used to draw 75 the upper portions of the webs 12 and 13 together to firmly clamp the tongue 20. In order that the heads 23 of the bolts, and the nuts 24, may bear on parallel faces, portions 25 and 26 of the outer surfaces of the webs 80 12 and 13 are vertically disposed, to provide such bearing surfaces. The usual nut and bolt locks, 27 and 28, may be used to prevent loosening of the bolts.

To take care of lateral thrusts, which 85 would otherwise tend to break off the tongue 20, the supporting web 13 is preferably continued upwardly for a short distance to form a flange 29 which extends approximately half way up the side of the rail head 90 10. This flange 29 forms an effective lateral support for the head especially on curves, where the side thrust is greatest.

The base member is preferably made in 95 lengths equal to the length of the head rails, which is usually thirty feet, and when the track is laid the head and base members are arranged to break joints, the result being a strong, continuous rail.

The base member can be secured to the 100

cross ties by any of the methods at present in use, such as by screw spikes, nail spikes, clamps, etc., driven through the outwardly projecting portions of the base or suitably 5 engaging them.

The base member not being subject to wear or impingement of the wheels, is not subject or liable to fracture, and the large area of supporting surface for the head 10 directly under the head reduces liability to fractures which may be induced by seams or other defects, and if fracture in the head should occur the disrupted pieces will be held securely in place. Because of the manner 15 of support of the rail head, rail heads of harder and more durable material can be used, resulting in economy from their longer wear. Renewals of the rail heads can be made without disturbing the base or support 20 on the cross ties, thus avoiding the removal or replacement of the fastenings, and thereby prolonging the life of the cross ties. In my compound rail a greater area of support to the rail head is obtained than it is 25 practicable to secure with a T-rail and because of the inclined flanges of the supporting member the weight or load is more uniformly and widely distributed over the base of the support and thence over a greater 30 area of the cross ties than it is possible to accomplish with the T-rails now commonly used.

To sum up the advantages of my invention, it will be apparent that the rail head 35 has a large area of direct support on the shoulders 14, 15 and great lateral support due to engagement of the tongue 20 by the shoulders and to the flange 29. Lateral stability is also increased by making the 40 outer bearing surface 17 slightly higher than the inner bearing surface 16, thus sloping the tread or upper surface of the rail slightly toward the center of the track to counteract the outward thrust of the wheels. 45 The outwardly flaring supporting webs distribute the load over a wide area, the base 11 being preferably about twice as wide as the distance between the lower parts of the webs. This distributes the loads over a 50 large area of the ties and tie plates may be dispensed with without detriment to wooden ties.

Having described the invention what is 55 claimed and desired to be secured by Letters-Patent is,

1. A compound rail comprising a head member and a base member, the head member comprising a head proper having downwardly and inwardly inclined under surfaces 60 18, 19, terminating in a downwardly projecting central tongue and the base member having upwardly and inwardly converging webs, the upper edges of which are fitted to the under surfaces of the head and to the

tongue and the lower edges of which are 65 integral with a base plate adapted to rest on the ties, the said base plate connecting the webs and extending laterally beyond the webs on both sides.

2. A compound rail comprising a head 70 member and a base member, the head member comprising a head proper having downwardly and inwardly inclined under surfaces 18, 19, terminating in a downwardly projecting central tongue having a reduced 75 neck and an enlarged lower portion and the base member having upwardly and inwardly converging webs, the upper edges of which are fitted to the under surfaces of the head and to the tongue and the lower edges of which are 80 integral with a base plate adapted to rest on the tie, the said base plate connecting the webs and extending laterally beyond the webs on both sides.

3. A compound rail comprising a head 85 member and a base member, the head member comprising a head proper having downwardly and inwardly inclined under surfaces 18, 19, terminating in a downwardly projecting central tongue and the base member having upwardly and inwardly converging 90 webs, the upper edges of which are fitted to the under surfaces of the head and to the tongue and the lower edges of which are integral with a base plate adapted to rest on 95 the ties, the said base plate connecting the webs and extending laterally beyond the webs on both sides, one of said webs having a flange extending above the said inclined 100 surfaces of the bottom of the rail and fitted to one side of the rail head to afford additional lateral support.

4. A compound rail comprising a head member and a base member, the head member comprising a head proper having downwardly and inwardly inclined under surfaces 105 18, 19, terminating in a downwardly projecting central tongue and the base member having upwardly and inwardly converging 110 webs, the upper edges of which are fitted to the under surfaces of the head and to the tongue and the lower edges of which are integral with a base plate adapted to rest on 115 the ties, the said base plate connecting the webs and extending laterally beyond the webs on both sides, the upper inclined surface of the outer web being slightly higher than the corresponding surface of the inner web, whereby the rail head is canted inward to assist in resisting the lateral thrust of the 120 car wheels.

5. A compound rail comprising a head member and a base member, the head member comprising a head proper having downwardly and inwardly inclined under surfaces 125 18, 19, terminating in a downwardly projecting central tongue and the base member having upwardly and inwardly converg-

ing webs, the upper edges of which are fitted to the under surfaces of the head and to the tongue and the lower edges of which are integral with a base plate adapted to rest on the ties, the said base plate connecting the webs and extending laterally beyond the webs on both sides, the said webs having portions of their outer surfaces in parallel vertical planes and being perforated through said planes to receive bolts, in combination 10 with suitable bolts and nuts for securing said head and base members together.

In testimony whereof I affix my signature.

WILLIAM G. COUGHLIN.
